UNITED STATES PATENT OFFICE

2,432,813

TOOL

Edward F. Scheide, Denver, Colo., assignor to
Benton F. Scheide, Denver, Colo.

Application June 22, 1946, Serial No. 678,639

1 Claim. (Cl. 306—35)

1

This invention relates to new and useful improvements and structural refinements in tools, more specifically, in mason tools, and the principal object of the invention is to provide a device of the character herein described, which embodies in its construction a hammer head and a scutch head, adapted for use with a common handle.

A further object of the invention is to provide a tool in which novel means is employed for detachably mounting either of the aforementioned heads at the end of the handle.

Another object of the invention is to provide a tool wherein the heads may be readily and conveniently interchanged.

An additional object of the invention is to provide a tool which is simple in construction and which cannot easily become damaged.

A still further object of the invention is to provide a tool which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a top plan view of the invention, showing the same in readiness for use as a mason's hammer.

Figure 2 is a cross-sectional view, taken substantially in the plane of the line 2—2 in Figure 1.

Figure 3 is an elevational view of the head receiving portion of the handle used in the invention, said view being taken in the direction of the arrow 3 in Figure 2.

Figure 4 is a fragmentary plan view of the hammer head.

Figure 5 is a cross-sectional view, taken substantially in the plane of the line 5—5 in Figure 4.

Figure 6 is an underside plan view of the subject shown in Figure 4.

Figure 7 is a cross-sectional view, taken substantially in the plane of the line 7—7 in Figure 3.

Figure 8 is a cross-sectional view, taken substantially in the plane of the line 8—8 in Figure 3.

Figure 9 is a fragmentary elevational view, taken in the direction of the arrow 9 in Figure 3.

Figure 10 is a top plan view of the scutch head, and

Figure 11 is a fragmentary side elevation, showing the invention in readiness for use as a scutch.

Like characters of reference are used to designate like parts in the specification and throughout the several views.

Referring now to the accompanying drawings 55 A tool comprising in combination, a working

2

in detail, the invention embodies in its construction, a hammer head 15, assuming any suitable configuration and being provided with a handle receiving bore 16 and with a countersink 17 at the outer end of this bore, as is best shown in Figures 2 and 5.

A handle designated generally by the reference character 18 consists of the body portion 19 molded upon, or otherwise suitably secured to a central core 20, the latter projecting at one end from the body portion 19 and being provided with a shoulder 21.

This shoulder is substantially elliptical in cross-sectional configuration and is formed integrally with a shank 22, this in turn, being provided with a screw threaded portion 23.

The shank 22 is provided at the base thereof with a pair of diametrically opposed lugs 24, these being substantially triangular in form, with the base thereof being disposed on the end surface portions 25 of the aforementioned shoulder 21.

The shank 22 is removably receivable in the bore 16 of the head 15, with the lugs 24 engaging a pair of diametrically opposed recesses 26 provided in the inner end of the bore 16. It will be noted that the recesses 26 are configurated complementarily to the lugs 24.

A nut 27 is positioned on the threaded portion 23 of the shank 22, said nut being formed with a frusto-conical portion 28 which is adapted to engage the aforementioned countersink 17. It will be noted that in this manner, the head 15 will be firmly yet detachably secured to the handle 18, since the tightening of the nut 27 will force the lugs 24 into stronger and stronger engagement, so to speak, with the recesses 26.

The hammer head 15 may be removed from the handle 18 by simply unscrewing the nut 27, whereupon the scutch head 29 may be attached 40 to the handle, as is best shown in the accompanying Figures 10 and 11.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

I claim as my invention:

A tool comprising in combination, a working

head provided with a handle receiving bore and with a countersink at the outer end of said bore, an elongated handle formed at one end thereof with a diametrically reduced portion providing a shank and an annular seat, a pair of wedge-shaped lugs formed integrally with said handle and projecting from said seat to the diametrically opposite sides of said shank, said shank being removably receivable in said bore and projecting outwardly from the countersunk end thereof, said bore being formed with complementary recesses adapted to receive said lugs, the projecting end portion of said shank being screw-threaded, a retaining nut provided on said screw-threaded portion, and a frusto-conical portion formed on said nut, said frusto-conical portion engaging said countersink.

EDWARD F. SCHEIDE.
